DESIGN FOR A LIPSTICK HOLDER

Louis Albert Samstag, New York, N. Y.

Application August 13, 1936, Serial No. 64,384

Term of patent 3½ years

To all whom it may concern:

Be it known that I, Louis Albert Samstag, a citizen of the United States, residing in New York, county and State of New York, have invented a new, original, and ornamental Design for a Lipstick Holder, of which the following is a specification, reference being had to the accompanying drawing, forming part thereof.

Fig. 1 is a top plan view of a lipstick holder showing my new design; and

Fig. 2 is a face elevational view of the same. The dominating feature of my design resides in the combination with the cylindrical body member shown of a surmounting ornamental dome-like member having the chased decorative formation as shown in the drawing.

I claim:

The ornamental design for a lipstick holder as shown and described.

LOUIS ALBERT SAMSTAG.
